DESIGN FOR A REMOTE CONTROL BOX FOR A MOTION PICTURE DISPLAY MACHINE

Arthur H. Bouterious, Oakland, Calif., assignor to
Mills Sales Company, Ltd., Oakland, Calif., a
corporation of Nevada

Application August 6, 1941, Serial No. 102,709

Term of patent 3½ years

To all whom it may concern:

Be it known that I, Arthur H. Bouterious, a citizen of the United States and a resident of Oakland, county of Alameda, State of California, have invented a new, original, and ornamental Design for a Remote Control Box for a Motion Picture Display Machine, of which the following is a specification, reference being had to the accompanying drawing, forming part thereof.

Figure 1 is a perspective view of a remote control box for a motion picture display machine showing my new design.

Figure 2 is a top plan view thereof.

I claim:

The ornamental design for a remote control box for a motion picture display machine, substantially as shown.

ARTHUR H. BOUTERIOUS.
